UNITED STATES PATENT OFFICE.

FRANCIS W. WEBB, OF CREWE, COUNTY OF CHESTER, ENGLAND.

LOCOMOTIVE AND TRACTION ENGINE.

SPECIFICATION forming part of Letters Patent No. 270,167, dated January 2, 1883.

Application filed June 7, 1882. (No model.) Patented in England March 16, 1881, No. 1,128; in Belgium July 30, 1881, No. 55,166, and in France September 27, 1881, No. 143,927.

To all whom it may concern:

Be it known that I, FRANCIS WILLIAM WEBB, of Crewe, in the county of Chester, England, a subject of the Queen of Great Britain, have invented certain new and useful Improvements in Locomotive and Traction Engines, of which the following is a specification.

My invention consists in certain improvements in compound-working engines by which they are rendered more compact and efficient and capable of being worked either compound or simple to better advantage than has heretofore been possible. I make the engine with three cylinders—two outside and one inside the framing in the central line of the engine. I prefer to place the outside cylinders behind the leading carrying-wheels or bogie, as the case may be, and to connect their pistons with cranks, at right angles to each other, placed on the ends of the axle of the pair of wheels which are usually placed behind the fire-box, these wheels having been hitherto in some cases coupled by coupling-rods to the pair of driving-wheels on an axle in front of the fire-box; but instead of so coupling them I carry the last-named pair of wheels on a cranked axle, to which the piston or pistons of the inside central cylinder are connected. When desiring to work compound I prefer to take the steam from the boiler first into the pair of outside cylinders, which are connected, as before stated, to drive the same axle, and cause the exhaust-steam from these cylinders to enter a chamber, which may be a part of the boiler, but made separate or partitioned from the high-pressure steam and water in the boiler. By this means the exhaust-steam from the first pair of cylinders is more or less reheated. From the exhaust-pipes, chamber, or receptacle I convey the steam to the valve-chest of the inside central cylinder, from which it finally exhausts and escapes into the atmosphere in the ordinary manner. But though I prefer to work the steam as explained it may be used the reverse way—that is, the steam direct from the boiler may be first worked in the inside central cylinder, the exhaust-steam from this high-pressure cylinder passing on, after being reheated, as above explained, to the outside or low-pressure cylinders, and from thence into the atmosphere. In both modes of working

the steam above described the capacity of the high and low pressure cylinders are properly proportioned one to the other to give the desired expansion of the steam, as is well understood. The steam and exhaust pipes may be so arranged that steam may be taken direct from the boiler to all or any of the cylinders, and all or any of the cylinders so supplied with steam direct from the boilers may exhaust directly into the atmosphere, or through any ordinary condenser-pipes in the water tank or tender, and from thence into the air. The cranked axle of the pair of wheels driven by the inside central cylinder may be made to have a side or radial motion, so as to facilitate the working round curves; or the axle of the front or leading pair of wheels may be made to have lateral or radial movement, instead of such movement being arranged in the cranked axle. When locomotives are required with more adhesion than can be obtained from two pairs of wheels, then the additional driving-wheels are placed behind the wheels hereinbefore mentioned as driven from the outside cylinders, and the additional wheels are coupled with the last-named in the ordinary manner by coupling-rods.

Any ordinary form or construction of valve-gear may be used and combined with locomotive-engines arranged as above described; but for my improved combination I prefer to employ gear similar to that for which Letters Patent were granted to David Joy, dated the 10th day of January, 1882, No. 252,224.

Figure 1 is a side elevation, partly in section, Fig. 2 an end elevation, and Fig. 3 a plan section, illustrating my improved arrangement of cylinders and valve-gear. Fig. 4 is a sectional elevation, and Fig. 5 a sectional plan, which illustrate my improved method of conveying the steam from the boiler to the high-pressure cylinders, and from the latter to the low-pressure central cylinder. Fig. 6 represents a side elevation of a locomotive illustrated by Figs. 1, 2, and 3 when a third pair of driving-wheels are used, coupled by ordinary coupling-rods in the usual manner with the axle driven from the outside cylinders, *a*. Fig. 7 is a detached sectional elevation, showing an arrangement of valve which may be used in combination with the other arrangements for causing the low-

pressure central cylinder to be supplied either with steam direct from the boiler or from the exhaust of the high-pressure outside cylinders, and for causing the exhaust-steam from the latter to pass directly to the atmosphere when steam direct from the boiler is supplied to the low-pressure cylinder.

Referring now to Figs. 1, 2, 3, and 6, the parts to be particularly referred to are only represented diagrammatically or by single center lines. These figures represent a locomotive with two pairs, A and B, of carrying-wheels on independent or uncoupled axles, and with a pair of carrying or pilot wheels, W, in front.

15 *a* are two outside cylinders, the piston-rods *a'* of which are jointed with connecting-rods *a''*, that are attached to cranks *a'''* on the driving-wheels B, behind the fire-box *x*, the cranks on this axle being set at right angles to each other. The axle *b* in front of the fire-box is cranked at the center (see Fig. 3) for a connecting-rod, *b'*, attached to the piston-rod *b''* of a single cylinder, *b'''*, carried in the middle of the framing of the engine.

25 The piston-rods and their guides and the connecting-rods may be of ordinary construction. The valves and valve-gear may be of ordinary construction, but I prefer and have indicated in Fig. 1 valve gear similar to what 30 is known as "Joy's valve-motion," hereinbefore referred to, as it is simple and leaves space for long journals, which I prefer to form on the axles.

For the valve of each outside cylinder there 35 is separate gear formed by a lever, *c*, one end of which is jointed to the connecting-rod *a''*. The other end can slide freely in a tube or guide, *c'*, mounted on a pivot or on trunnions upon the framing, so as to swivel freely to the 40 motion imparted by the said lever *c*.

Jointed to the lever *c* is one end of another lever, *c''*, or it is a double lever—one on each side of the lever *c*—and this single or double lever *c''* is also jointed near its other end to a 45 slide-block, *c'''*, which can slide up and down in the curved slot in a circular block, *c''''*, arranged to be oscillated in a bracket carried on the framing by a connection with the reversing-lever, which is attached to an arm or lever, 50 *c'''''*, secured to or formed on the circular block. That end of the lever *c''* projecting past the joint with the slide-block *c'''* is jointed with the rod *c'''''*, connecting it with the valve-spindle *c'''''* to be actuated. A similar arrangement of 55 mechanism is employed for working the valve of the inside central cylinder, *b'''*, except that in this case the lever *C*, corresponding to the lever *c* for the outside cylinders, does not slide in a swivel-tube, but its end is jointed to one 60 end of a radius-rod, *c'''''*, the other end of which is jointed to the framing.

There is one reversing-shaft, *d*, in suitable bearings on the framing, having an arm, *d'*, upon it, jointed at one end with a rod, *d''*, (represented by a dotted line,) which at the other end is jointed with an ordinary reversing lever or screw or other arrangement. The revers-

ing-shaft *d* has also two arms, *d'''*, upon it—one for the valve-gear of each outside cylinder—which arms are each connected by a rod, *d''''*, 70 with the arm *c'''''* from each circular block *c''''*, and the reversing-shaft *d* has another arm, *d'''''*, which is connected by a rod, *d''''''*, with the arm *c'''''* from the reversing-block for the valve of the inside cylinder, the connecting-rod to the 75 valve-spindle of this cylinder being represented by the line *c'''''*.

In the arrangement shown by Figs. 1, 2, and 3 the steam passes from the boiler through the smoke-box tube-plate into a T-branch, *e*, with which pipes *e'* are joined, one of which passes on each side in a curve close or nearly close to the casing of the smoke-box *e''*, and then each pipe bends to a horizontal position and passes to and is jointed with the steam-chest 85 of its respective outside high-pressure cylinder *a*. The exhaust-pipes *f* from the outside high-pressure cylinders, *a*, pass horizontally to the smoke-box, then each ascends vertically, keeping about to the curve of the casing of the smoke-box, and passes round and then descends to the valve-chest of the low-pressure inside cylinder, *b'''*, each pipe thus passing round the smoke-box and forming a separate junction with the valve-chest. The exhaust from the 90 central low-pressure cylinder passes from it up the blast-pipe *f''*, between the two exhaust-pipes *f* from the high-pressure cylinders *a*. No claim is, however, made herein to this manner of 95 conducting the steam.

In Fig. 6 a locomotive similar to that illustrated in Fig. 1 is shown, with a third pair of driving-wheels coupled by ordinary coupling-rods in the usual manner with the wheels driven from the outside cylinders, *a*.

In Fig. 4 the steam from the boiler is taken to the outside high-pressure cylinders, *a*, as hereinbefore described in reference to Figs. 1, 2, and 3, and the exhaust-steam from the high-pressure cylinders is taken by pipes *f* horizontally; but when the pipes have arrived near the smoke-box one exhaust-pipe is crossed over and branches into the other, which passes forward into the smoke-box and ascends close, or nearly so, to the tube-plate, and passes 110 through it and then through a horizontal pipe, *f'*, suspended in the steam-space of the boiler, and then out through the tube-plate into the smoke-box, and down close to the tube-plate by a pipe, *f''*, to form a junction with the 115 valve-chest of the low-pressure inside cylinder, *b'''*.

By the arrangements described in reference to Figs. 1, 2, and 3 the driving-wheels are only coupled together by their adhesion to the rails 120 and by the central low-pressure cylinder, (when working compound,) being dependent for their supply of steam upon the high-pressure cylinders; but the cranks of the high-pressure cylinders will always be in a position to start the 130 engine, and the low-pressure cylinder will also act, except when on the center, when, after a slight movement has been made, the low-pressure cylinder will also assist in starting

the engine. There is a pipe and valve or cock provided between the steam in the boiler and the valve-chest of the central low-pressure cylinder, which cock or valve may be opened by a convenient handle to allow a supply of steam direct from the boiler to pass to the valve-chest of the low-pressure cylinder at starting, before the first stroke of the high-pressure cylinders has taken place, and this temporary supply of steam may be allowed to pass through a valve to reduce its pressure, if desired.

Referring now to Fig. 7, which is a sectional elevation showing an arrangement of valve for causing the low-pressure cylinder to be supplied either with steam directly from the boiler or from the exhaust of the high-pressure cylinders, and for causing the exhaust-steam from the latter to pass directly to the atmosphere when steam direct from the boiler is supplied to the low-pressure cylinder, b^3 is supposed to be a part of the low-pressure cylinder, of which b^4 is the valve-box. The lid to this valve-box is formed with ports and passages and with a valve-facing, and slide-valve b^5 , with a spindle, b^6 , for actuating it passing through a stuffing-box, and then connected by a rod or lever, shaft, and rods with any convenient lever or screw handle for moving the slide-valve to and fro. Steam direct from the boiler is brought by a pipe to a branch on the valve-chest at b^7 . Its pressure then acts to press the slide-valve b^5 against its facing. In the position in which the valve b^5 is shown steam direct from the boiler is passing to the low-pressure valve-chest. The exhaust-steam from the high-pressure cylinders is brought by the pipes to branches from the cavity b^8 , and in the position in which the valve is shown in full line it passes through the cavity of the valve b^5 into the passage b^9 , and from thence is conveyed by a passage or pipe to the exhaust-port of the central low-pressure cylinder or to the blast-pipe. When the slide-valve b^5 is moved to the opposite extreme to that in which it is shown, as in dotted line, the port supplying direct boiler-steam to the low-pressure valve-chest and the port to the exhaust-passage b^9 are covered or closed, but another port is opened between the cavity b^8 for exhaust from the high-pressure cylinders to the valve-chest of the low-pressure cylinder. With this arrangement of valve b^5 the cylinders may be worked either by steam direct from the boiler or upon the "compound" system, and can be readily changed from one to the other at pleasure. This arrangement of valve b^5 may also be used for starting the engine and for admitting a temporary supply of steam direct from the boiler to the central low-pressure cylinder for starting the engine.

I am aware that in English Letters Patent No. 1,857 of 1872 a locomotive is illustrated and described in which two outside cylinders drive a single axle having carrying-wheels, and two inside cylinders drive another axle, not coupled with the first, and also having carrying-wheels, and that it was proposed to work such engine.

compound, somewhat after the manner herein described by me. I therefore make no claim to any such organization, but distinctly limit myself to the specific construction herein claimed, involving the use of a single inside cylinder placed in the central line of the engine. By such a construction I am enabled to produce an engine of great compactness, strength, and efficiency, and one not open to the objections which have heretofore prevented the introduction and practical use of the machine disclosed in the British patent referred to.

Having particularly described the nature of my invention and the modes of carrying it into effect, I claim as my invention—

1. The combination of the two pairs of driving and carrying wheels, a pair of outside cylinders for driving one pair of said wheels, and a single inside cylinder placed in the central line of the engine for driving the other pair of wheels, substantially as set forth.

2. The combination of the two separately-driven or uncoupled pairs of driving and carrying wheels, the outside cylinders worked by steam direct from the boiler for independently driving one pair of said wheels, and a single inside cylinder placed in the central line of the engine and worked by the exhaust-steam from the outside cylinders to independently drive the other pair of wheels, substantially as set forth.

3. The combination of two pairs of driving and carrying wheels, cylinders for driving them, one pair of said wheels being worked by steam direct from the boiler and the other pair of wheels being worked by the exhaust, and the pipe or pipes which convey the exhaust-steam through the boiler of the engine, substantially as set forth.

4. The combination of two pairs of driving and carrying wheels, two outside cylinders worked by steam direct from the boiler for driving one pair of wheels, a single central inside cylinder for driving the other pair of wheels, and valve mechanism, substantially such as described, and illustrated in Fig. 7, whereby the single central cylinder may be worked by the exhaust-steam from the outside cylinders or by steam direct from the boiler, substantially as set forth.

5. The combination of a pair of driving and carrying wheels, two outside cylinders worked by steam direct from the boiler for driving said wheels, another pair of wheels coupled to and in rear of the pair above mentioned, another pair of driving and carrying wheels, and a single central inside cylinder for driving said wheels worked by the exhaust-steam from the outside cylinders, substantially as set forth.

In testimony whereof I have hereunto subscribed my name this 23d day of May, A. D. 1882.

FRANCIS WILLIAM WEBB.
